United States Patent Office.

EDWARD JOHN ARENS, OF BOSTON, MASSACHUSETTS.

Letters Patent No. 66,280, dated July 2, 1867.

IMPROVEMENT IN CUTTERS FOR PLANING MOULDINGS.

The Schedule referred to in these Letters Patent and making part of the same.

TO ALL WHOM IT MAY CONCERN:

Be it known that I, EDWARD J. ARENS, of Boston, in the county of Suffolk, and State of Massachusetts, have invented a new and useful Improvement in Moulding-Cutters; and I do hereby declare the following to be a full, clear, and exact description of the nature thereof, sufficient to enable others skilled in the art to which it appertains to fully understand and use the same, reference being had to the accompanying drawings, making part of this specification, in which—

Figure 1 is a perspective view of the cutters illustrating my invention as applied to a moulding-cutter head.

Figure 2 is a front view of the cutting edge.

Figure 3 is a view of the back of the cutter.

Figure 4 is a view of the face of the cutter.

Figure 5 is a view of the back end thereof.

Similar letters of reference indicate corresponding parts in the several figures.

This invention of a cutter intended for forming mouldings consists in so constructing its face that it will cut equally well across and against the grain as with the grain, and produce a smooth cut in each case. The form or pattern of the cutter is first made in the stock. The face side is then planed or taken out so as to leave certain angles or ridges relatively to said pattern that when the back side is sharpened the cutting portion for each member will consist of two diagonal faces meeting at the ridges, and whose lower ends unite with those of their adjacent cutting portions and form the parts which cut the grooves or channels between the beads or members. The knives or cutters will be mounted on a revolving arbor and will always cut downward and upward, and the cutting will first commence at the lower part of the diagonal faces and end at the meeting point, thereby the cutting will be diagonally from these lower parts to the meeting point. There will be no tearing or ripping of the wood, whether the member be large or of the most minute pattern, regardless of the grain of the wood, whether across, against, or with it.

In the drawings, A represents the cutter, consisting of a stock, whose face is represented at B and back at C. D represents the cutting edge and E the back end of the cutter. A suitable pattern is made on the stock, and the face is then cut out or planed longitudinally, so as to leave certain longitudinal ridges or angles relatively to the pattern. The back is now properly ground to an edge, and it will be perceived that the cutting portion for each member will consist of two diagonal faces *a b*, which meet at a certain point, *c*, of the angle on the face of the cutter. When the cutter is applied to an ordinary cutter-head, and suitable power applied thereto, the cutter will make a striking diagonal or slanting cut, and consequently the member will be cut smooth easier and with less power than ordinary. The wood to be employed for moulding can be selected without regard to its grain, for the cutter will perform its work equally well, whether across, against, or with the grain.

Having thus described my invention, what I claim as new, and desire to secure by Letters Patent, is—

A moulding-cutter whose cutting edges for each member consist of diagonal faces meeting at the angle or ridge on the face of the cutter relatively to the form or contour of the moulding, substantially as described.

EDWARD JOHN ARENS.
